DRILL STEEL GUIDE

Charles F. Osgood, Claremont, N. H., assignor to
Joy Manufacturing Company, a corporation of
Pennsylvania

Continuation of application Serial No. 539,832,
June 12, 1944. This application June 18, 1947,
Serial No. 755,427

20 Claims. (Cl. 255—51)

1

This invention relates to rock drills and more particularly to improvements in a guide for the drill steel of a mounted rock drill.

In mounted rock drills, the drilling motor which actuates the drill steel is usually mounted on the guideways of a guide shell, and the latter is, in turn, suitably supported with respect to the work. In such rock drills, a guide or centralizer is usually provided at the front end of the guide shell for centering the drill steel during starting of a drill hole, and means is usually provided for automatically releasing the guide from the drill steel when the drilling motor approaches the guide so that the forward portion of the drilling motor may be fed along the shell guideways forwardly past the guide. Frequently, release of the guide is effected by direct contact by the forward end of the drilling motor therewith. In known devices, the steel guide is positively locked in guiding position, and, when the locking means is released by engagement of the drilling motor therewith, the guide is moved out of guiding relation with the drill steel into a position out of the path of movement of the drilling motor by torsion springs or the like.

In a preferred embodiment of the present invention, the steel guiding elements of the guide may be mounted on a support for lateral swinging movement into and out of guiding relation with a drill steel to be guided and for bodily movement in a direction lengthwise of the drill steel. The guiding elements of the guide may be moved bodily in a longitudinal direction by direct engagement of the forward end of the drilling motor therewith, and, as the drilling motor is fed forwardly along the guide shell, the guiding elements are shoved forwardly. Means may be provided so that concurrently with and as a result of such bodily movement of the guiding elements, the latter are positively swung outwardly about their pivots out of guiding relation with the drill steel and into a wide open position wherein the forward portion of the drilling motor may move between the guiding elements forwardly past the guide. In a preferred embodiment, such outward swing of the arms, as the latter are moved bodily, may be effected by cams or spirally arranged grooves or slots. The chuck housing of the drilling motor may engage the steel engaging portions of the arms to shove the latter forwardly, and, as these steel engaging portions move laterally into contact with the sides of the chuck housing, there may be provided supplemental projections on the arms which move into engagement with the chuck

housing so that the drilling motor may continue to shove the arms forwardly to effect outward swinging of the arms into a position out of the path of the drilling motor. In another embodiment, the final outward swinging movement of the arms may be effected by supplemental cam means under the action of compression springs so that, as the steel engaging portions of the arms move laterally out of contact with the sides of the chuck housing, the springs may move automatically the arms into their wide open position wholly independently of any engagement of the arms with the drilling motor. The cam means may assume various forms, and in different embodiments may consist of cam grooves or slots or separate projecting cam portions with which the arms cooperate, and the cams may be arranged at the arm pivots or intermediate the arm pivots. Also, outward swing of the arms, as the latter are moved bodily, may be positively effected by means other than cams, and it is intended to include, within the scope of the present invention, any means for effecting concurrent bodily and pivotal movements of the arm wherein the pivotal movement is effected as a result of the bodily movement. In such constructions, it is unnecessary to provide torsion springs, or the like, for swinging the arms apart.

It is an object of the present invention to provide an improved drill steel guide wherein the guiding elements thereof may be moved bodily by direct engagement of the drilling motor with the guiding elements as the motor is fed forwardly along its guide shell, together with means for positively swinging the guiding elements laterally out of guiding relation with the drill steel concurrently with and as a result of such bodily movement of the guiding elements. Another object is to provide an improved drill steel guide having improved means for swinging the guiding elements laterally away from the drill steel as the guiding elements are moved bodily in a longitudinal direction. A further object is to provide an improved drill steel guide wherein the lateral movement of the guiding elements away from the drill steel occurs as a result of bodily movement of the guiding elements in a direction lengthwise of the drill steel. A still further object is to provide an improved drill steel guide including guide arms mounted for bodily and pivotal movements on a support and having associated therewith improved cam means whereby, as the arms are moved bodily, they are concurrently swung laterally. A still further object is to provide an improved drill steel guide having im-

proved means for effecting initial or partial releasing movement of the guiding elements laterally away from the drill steel and having improved supplemental means for thereafter effecting final or complete movement of the guide arms into their wide open, non-guiding position. A further object is to provide an improved drill steel guide of a novel design and construction. These and other objects and advantages of the invention will, however, more fully appear.

This application is a continuation of my application, Serial No. 539,832, filed June 12, 1944, now abandoned.

In the accompanying drawings there are shown for purposes of illustration two forms which the invention may assume in practice.

In these drawings:

Fig. 1 is a fragmentary side elevational view of a rock drill with which an illustrative embodiment of the drill steel guide is associated.

Fig. 2 is a front end elevational view of the rock drill and steel guide shown in Fig. 1, the drill steel being shown in cross section.

Fig. 3 is a cross-sectional view taken substantially on line 3—3 of Fig. 1, showing the drill steel guide in its guiding position.

Fig. 4 is a sectional view, similar to Fig. 3, showing the drill steel guide in its released, non-guiding position.

Fig. 5 is a horizontal sectional view taken substantially on line 5—5 of Fig. 1.

Fig. 6 illustrates one of the cam slots shown in Fig. 5, on an enlarged scale.

Fig. 7 is a fragmentary side elevational view, similar to Fig. 1, illustrating a rock drill equipped with a drill steel guide of modified construction.

Fig. 8 is a front end elevational view of the rock drill and drill steel guide shown in Fig. 7, the drill steel being shown in cross section.

Fig. 9 is a cross-sectional view taken substantially on line 9—9 of Fig. 7, showing the drill steel guide in its guiding position.

Fig. 10 is a sectional view, similar to Fig. 9, showing a drill steel guide in its released non-guiding position.

Fig. 11 is a horizontal sectional view taken substantially on line 11—11 of Fig. 7.

Fig. 12 is a detail view, illustrating one of the cam slots shown in Fig. 11 on an enlarged scale.

In both illustrative embodiments of the invention, the improved drill steel guide is shown associated with a conventional rock drill of the mounted drifter type. It will be evident, however, that the invention may be embodied in tools of other types.

The rock drill disclosed herein comprises a conventional drilling motor or drill steel actuator 1 slidably guided on a conventional guide shell 2. The drilling motor has a motor cylinder 3 containing a reciprocable hammer piston for percussively actuating a drill steel 4, the latter carrying a usual drill bit 5 and being suitably supported in a usual chuck within a front chuck housing 6, suitably attached to the forward end of the motor cylinder. The motor cylinder has usual lateral guides 7, 7 slidably received in longitudinal guideways 8, 8 of the guide shell. The drilling motor may be fed in any well known manner along the shell guideways toward and from the work by any suitable means. Since, as above stated, the rock drill is of a conventional design and is well known to those skilled in the art, further description and illustration thereof are herein unnecessary.

In the embodiment shown in Figs. 1 to 6 in-

clusive, the drill steel guide is generally designated 10 and comprises front and rear transverse plates 11 and 12 attached, as by parallel, longitudinal bolts 13, to the front end of the guide shell 2. These plates 11, 12 are held in spaced relation by spacing sleeves 14 surrounding the bolts intermediate the plates, and these sleeves are suitably secured against rotation relative to the plates. Pivotedly mounted on the

spacing sleeves are the hubs 15 of a pair of guide arms 16, and each of the latter has an appropriately shaped steel engaging portion 17. The steel engaging portions 17, when the guide arms are swung together as shown in Fig. 3, embrace the body of the drill steel 4 to hold the drill bit

5 centered during starting or "spotting" of a drill hole in a well known manner. The hubs 15 of the guide arms are also mounted on the spacing sleeves 14 for bodily sliding movement in a longitudinal direction relative to the drill steel. Any

20 suitable means may be provided for effecting lateral swinging movement of the arms about their pivots concurrently with and as a result of such bodily movement, and preferably may comprise cam-follower pins or other projections 18 formed on screws 19 secured to the arm hubs, and these follower pins are engaged in cam slots or grooves

25 20 in the spacing sleeves. Encircling the spacing sleeves intermediate the arm hubs and the front plates are relatively light compression springs 21 which constantly urge the arms in a rearward direction. The arm hubs enclose the cam grooves in all positions of bodily movement of the guide arms so that access of dirt to the

30 35 grooves is substantially prevented. Each cam groove, as shown in Fig. 6, has a straight rearward longitudinal portion 22, a forwardly and outwardly inclined portion 23 and a lateral recess portion 24. The arms are yieldingly held

35 40 in a rearward guiding position in engagement with the rear plate in guiding relation with the drill steel, as shown in Fig. 3, by the springs 21, and the pins or projections 18 are, at that time, received in the straight rearward portions 22 of the cam grooves so that the arms are positively

45 50 locked against outward swinging movement with respect to the drill steel. When the front chuck housing 6 of the drilling motor engages the rear surfaces of the steel engaging portions 17 of the guide arms, the latter are shoved bodily along the spacing sleeves 14 to a forward direction, and the pins 18, as the arms move forwardly, move along the inclined portions 23 of the cam grooves,

55 60 thereby effecting positive lateral swinging of the arms outwardly away from the drill steel. When the guide arms assume the partially released position indicated in dotted lines in Fig. 4, at the outer sides of the chuck housing, projections 25, extending inwardly from the arm hubs

drilling motor to bring the pins 18 into the locking recesses 24 so that the guide arms are locked in their wide open released position. The recessed ends of the cam grooves also limit outward swing of the arms. When the guide arms are wide apart, as shown in full lines in Fig. 4, the forward portion of the drilling motor may move between the guide arms, forwardly past the guide.

The modified embodiment, shown in Figs. 7 to 12 inclusive, is generally similar to that above described. In this form, however, the arm projections 25 are omitted and the final outward swinging movement of the guide arms to wide open position is effected automatically by the cams and springs as hereinafter described. In this construction, the transverse plates, attaching bolts and spacing sleeves are similar to those above described. Pivotally mounted on the spacing sleeves are the hubs 30 of a pair of guide arms 31, the latter each having an appropriately shaped steel engaging portion 32 adapted to embrace the body of the drill steel to maintain the latter centered during starting of a drill hole. Secured to the arm hubs are screws 33 on which are formed cam-follower pins or projections 34 which project into cam slots or grooves 35. As in the other embodiment, the arm hubs enclose the cam grooves in all position of bodily movement of the arm so that dirt cannot enter the grooves. Encircling the spacing sleeves intermediate the arm hubs and the front plate are relatively light coil compression springs 36. As shown in Fig. 12, each of the cam grooves has a straight rearward longitudinal portion 37, a forwardly and outwardly inclined portion 38, and a rearwardly inclined portion 39. The arms are held in a rearward position, shown in Fig. 9, against the rear plate in guiding relation with the drill steel, by the springs 36 with the follower pins or projections 34 received in the straight rearward portions 37 of the cam grooves so that the arms are at that time positively locked against outward swinging movement with respect to the drill steel. When the front chuck housing of the drilling motor engages the rear surfaces of the steel engaging portions 32 of the guide arms and the latter are shoved bodily in a forward direction along the spacing sleeves, the follower pins 34 move along the forwardly inclined portions 38 of the cam grooves, thereby effecting lateral swinging of the arms away from the drill steel. When the arms assume the partially released dotted line position shown in Fig. 10 at the outer sides of the chuck housing, the pins 34 are in the right-hand dotted line position shown in Fig. 12 at the outer ends of the inclined groove portions 38, and the arms are then free to move rearwardly relative to the chuck housing under the influence of the coil springs 36 and the pins 34, as the arms move rearwardly, engage the rearwardly inclined portions 39 of the cam grooves to effect further lateral swinging of the arms into their completely released non-guiding position out of the path of the drilling motor, as shown in full lines in Fig. 10. Accordingly, the final outward swinging movement of the guide arms from the position indicated in dotted lines in Fig. 10 to the full line position in that figure is effected independently of the drilling motor by the coil springs 36 and rearwardly inclined cam portions 39. The ends of the portions 39 of the cam slots lock the arms in their released position and serve to limit outward swing of the arms.

The general mode of operation of the embodiment of the drill steel guide, shown in Figs. 1 to 6 inclusive, is as follows: When it is desired to start or "spot" a drill hole, the guide arms 16 5 may be moved manually slightly forwardly and then inwardly about their pivots to release the pins 18 from the locking recesses 24 and thereafter the guide arms may be shoved inwardly and rearwardly into steel guiding position, as shown in Figs. 1 and 3, with the pins 18 received in the straight rearward portions 22 of the cam grooves so that at that time the arms are positively locked against outward swinging movement. As the drilling motor is fed forwardly 15 along the shell guideways 8, 8, the front chuck housing 6 engages the rear surfaces of the steel engaging portions 17 of the guide arms and, upon continued forward movement of the drilling motor, the guide arms are shoved forwardly bodily along the spacing sleeves to effect release of the pins 18 from the straight rearward portions 22 of the cam grooves and to move the pins forwardly along the inclined portions 23 of the cam grooves to swing the guide arms laterally 20 from the position shown in Fig. 3 to the partially released dotted line position shown in Fig. 4. As the steel engaging portions 17 of the guide arms move laterally to the sides of the chuck housing, the projections 25 on the guide arms 25 move into the path of the chuck housing so that the drilling motor, as it continues to move forwardly, moves the pins 18 further outwardly 30 along the inclined portions 23 of the cam grooves, to swing the arms further into their completely released non-guiding position, as shown in full lines in Fig. 4. When the projections 25 are positioned laterally at the sides of the drilling motor, the springs 21 move the arm hubs a slight distance rearwardly along the spacing sleeves to bring the pins 18 into the locking recesses 24 so that the guide arms are locked in their wide open position. When the guide arms are in their wide open position, the drilling motor may move between the guide arms forwardly in advance of the guide. Under certain conditions, the guide arms may be separately placed in guiding relation with the drill steel so that but a single guide arm may serve as a guide, as for instance, during "spotting" of a drill hole on an inclined working face when but a single guide arm will suffice to prevent lateral deflection of the drill 35 40 45 50 55 60 65 70 75

The mode of operation of the modified invention, shown in Figs. 7 to 12 inclusive, is generally similar to that above described in that, as the arms are moved forwardly bodily, they are concurrently swung outwardly out of guiding relation with the drill steel. In this instance, however, when the front chuck housing of the drilling motor engages the steel engaging portions 32 of the guide arms and shoves the guide arms forwardly bodily along the spacing sleeves, the pins 34 move forwardly out of the straight rearward portions 37 of the cam grooves and thereafter move along the inclined groove portions 38 to effect swinging of the guide arms laterally away from the drill steel to the partially released position indicated in dotted lines in Fig. 10. When the steel engaging portions 32 of the arms move laterally to the sides of the chuck housing, the coil springs 36 act to move the guide arms bodily rearwardly to bring the pins 34 into contact with the rearwardly inclined portions 39 of the cam grooves to complete the outward swinging of the arms from the dotted line position shown in

Fig. 10 to the wide open, non-guiding position shown in full lines in that figure. It is accordingly evident that the final swinging movement of the arms toward wide open position is effected by the cam grooves and coil springs wholly independently of the movement of the drilling motor along the shell guideways. When the pins 34 are positioned at the outer ends of the rearwardly inclined portions 39 of the cam grooves, the guide arms are locked in their wide open, released position so that the forward portion of the drilling motor may move between the guide arms forwardly in advance of the guide. When it is desired to move the guide arms inwardly into guiding relation with the drill steel, the operator may manually move the arms forwardly and inwardly to move the pins 34 out of the groove portions 39 into the groove portions 38, and thereafter the arms may be moved rearwardly and inwardly into guiding relation with the drill steel. When the pins 34 are received in the straight rearward portions 37 of the cam grooves, the arms are locked against outward swinging movement from their steel guiding position.

As a result of this invention, it will be noted that an improved drill steel guide is provided wherein, when the arms are moved bodily in a direction lengthwise of the drill steel, they are concurrently positively swung outwardly out of guiding relation with the drill steel. It will further be evident that by the provision of the improved cam means associated with the guide arms, the latter, as they are moved bodily in a forward direction, are positively swung outwardly about their pivots out of guiding relation with the drill steel. In one embodiment, the guide arms are moved out of guiding relation with the drill steel into their wide open, released position completely by direct engagement of the forward end of the drilling motor with the guide arms, while, in the other embodiment, initial lateral swinging movement of the guide arms is effected by the drilling motor and the final outward swinging movement of the guide arms is effected wholly independently of the drilling motor. In both embodiments, the improved drill steel guide is relatively simple and compact, and may be readily attached to a conventional guide shell with little or no modification. Other uses and advantages of the invention will be clearly apparent to those skilled in the art.

While there are in this application specifically described two forms which the invention may assume in practice, it will be understood that these forms of the same are shown for purposes of illustration and that the invention may be further modified and embodied in various other forms without departing from its spirit or the scope of the appended claims.

What I claim as new and desire to secure by Letters Patent is:

1. In a rock drill of the kind which includes a support along which a drill steel actuator is guided for movement toward the work, a drill steel guide carried by said support at the front end thereof and including a guide arm engageable with a drill steel to be guided, pivot providing and guiding means on said support for mounting said arm for pivotal movement about an axis parallel to the longitudinal axis of the drill steel into and out of guiding relation with the steel and for guided bodily movement in the direction of the axial line of the pivot lengthwise of the drill steel, said actuator as it moves forwardly along said support acting on said arm

5 to effect forward bodily movement thereof along said guiding means, and arm swinging means for swinging said arm laterally about its pivotal axis away from the drill steel as said arm moves forwardly bodily along said guiding means, said swinging means comprising cooperating swing-effecting elements respectively on said guiding means and said arm and having relative movement for imparting a lateral swinging force to said arm to swing the latter outwardly as the result of such forward guided bodily movement of said arm, and said arm having spaced lateral portions successively engageable by said actuator as the latter moves forwardly, said actuator first engaging one arm portion to move said arm bodily 10 to effect swinging of said arm outwardly about its pivot to effect partial lateral release of said arm from the steel and said other arm portion moving, upon partial release of said arm as aforesaid, into the path of said actuator as said first portion moves out of the path of said actuator, to effect by engagement with said latter portion further outward swinging of said arm about its pivot thereby completely to release said arm from the steel.

2. In a rock drill of the kind having a support along which a drill steel actuator is guided for movement toward the work, a drill steel guide carried by said support at the front end thereof and including a guide arm having a portion engageable with a drill steel to be guided, pivot providing and guiding means on said support for mounting said arm for pivotal movement about a longitudinal axis parallel to the longitudinal axis of the drill steel and for guiding said arm for bodily movement along a straight path in the direction of the axial line of the pivot lengthwise of the drill steel, said actuator as it moves forwardly along said support first engaging said arm-portion to effect bodily movement of said arm as aforesaid along said guiding means, and arm swinging means associated with said guiding means and coacting with said arm whereby the latter as it is moved bodily along said guiding means is swung outwardly about its pivot away from the drill steel to move said arm-portion laterally out of the path of said actuator, said arm having a lateral projection spaced from said steel engaging portion and swingable with said arm whereby when said arm has swung into its partially released position and said steel engaging portion thereof has moved out of the path of said actuator said projection has moved into the path of said actuator then, and said actuator engaging said projection to swing said arm about its pivot 30 completely into its fully released position wherein said projection is located out of the actuator path at the side of the actuator.

3. In a rock drill of the kind having a support along which a drill steel actuator is guided for movement toward the work, a drill steel guide carried at the front end of said support and including a guiding element engageable with the drill steel to be guided, movement permitting and guiding means on said support for mounting said guiding element for lateral movement in transverse planes into and out of guiding relation with the drill steel and for guiding said element for bodily movement along a straight path in a direction lengthwise of the drill steel, said actuator as it moves forwardly along said support engaging said guiding element to move the latter bodily along said guiding means, arm swinging means associated with said guiding means and coacting with said guiding element and including co-

operating swing-effecting elements, one on said guiding means and the other on said guiding element, for moving said guiding element laterally on its mounting means away from the drill steel, as said guiding element moves bodily along said guiding means in one direction, laterally into a partially released position, and means operative when said guiding element has moved into its partially released position and operating independently of movement of said actuator for completing the movement of said guiding element laterally along its mounting means into its completely released non-guiding position out of the path of said actuator, said last mentioned means moving said guiding element bodily along its guiding means to complete such lateral release of said guiding element.

4. In a drill steel guide, a guiding element engageable with a drill steel to be guided, movement permitting and guiding means for mounting said guiding element for lateral movement in transverse planes into and out of guiding relation with the drill steel and for guiding said element for bodily movement successively in opposite directions along a straight path extending lengthwise of the drill steel, means associated with said guiding means and coacting with said guiding element and including cooperating elements having relative movement, one on said guiding means and the other on said guiding element, for moving said guiding element laterally away from the drill steel as said element moves bodily in one direction along said guide means thereby to move said element into its partially released position, and guiding element moving means also associated with said guiding means and coacting with one of said moving-elements for moving said guiding element laterally on said mounting means into its completely released non-guiding position as said guiding element moves bodily along said guiding means in the opposite direction.

5. In a drill steel guide, a guiding element engageable with a drill steel to be guided, movement permitting and guiding means for mounting said guiding element for lateral movement in transverse planes into and out of guiding relation with the drill steel and for guiding said element for bodily movement along a straight path successively in opposite directions lengthwise of the drill steel, moving means for said guiding element associated with said guiding means and coacting with said guiding element and including cooperating elements having relative movement, one on said guiding means and the other on said guiding element, for moving said guiding element laterally out of guiding relation with the drill steel as said guiding element moves bodily in one direction along said guiding means, and locking means associated with said mounting means and operative as said guiding element moves bodily in the opposite direction along said guiding means for locking said guiding element in its completely released non-guiding position, said locking means cooperating with one of said cooperating elements of said moving means.

6. In a drill steel guide, a support, a pair of cooperating guide arms engageable with a drill steel to be guided, pivot providing and guiding means on said support for mounting said guide arms for relative pivotal movement about longitudinal axes parallel to the longitudinal axis of the drill steel into and out of guiding relation with the drill steel, said guiding means guiding said arms for bodily movement along straight

70

paths lengthwise of the drill steel, said arms having cam-engaging projections near the pivots thereof, and cams associated with said guiding means and having cam surfaces with which said projections respectively engage for swinging said arms outwardly about their pivots away from the drill steel as said arms concurrently move bodily along said guiding means, said cam-engaging projections moving along said cam surfaces as said arms move bodily as aforesaid.

7. In a drill steel guide, a guiding element engageable with a drill steel to be guided, movement permitting and guiding means for mounting said guiding element for relative lateral movement in transverse planes in opposite directions into and out of guiding relation with the drill steel and for guiding said element for bodily movement along a straight path successively in opposite directions lengthwise of the drill steel, movement-effecting means associated with said guiding means and coacting with said guiding element and including cooperating elements having relative movement, one on said guiding means and the other on said guiding element, for moving said guiding element laterally on said mounting means out of guiding relation with the drill steel as said guiding element moves bodily in a forward direction along said guiding means, and locking means thereafter effective as said guiding element moves bodily in the rearward direction along said guiding means and cooperating with one of said cooperating elements for moving said guiding element for locking the latter in its outermost released non-guiding position.

8. In a drill steel guide, a guide arm engageable with a drill steel to be guided, a pivot providing and guiding means for pivotally mounting said guide arm to swing in transverse planes about an axis parallel to the longitudinal axis of the drill steel into and out of guiding relation with the drill steel and for guiding said arm for bodily movement in the direction lengthwise of the drill steel, and arm swinging means cooperating with said guiding means and with said arm and including cooperating arm swinging elements having relative movement, one on said guiding means and the other on said arm, for swinging said arm outwardly about its pivot away from the drill steel as said arm moves bodily along said guiding means, and said mounting and guiding means maintaining the arm pivot parallel to the longitudinal axis of the drill steel during such swinging and bodily movements of said arm.

9. In a drill steel guide, the combination comprising a support, a guiding element engageable with a drill steel to be guided, movement permitting and guiding means on said support for mounting said guiding element for lateral movement in transverse planes into and out of guiding relation with the drill steel and for guiding said guiding element for bodily movement along a straight path in a direction lengthwise of the drill steel, and movement-effecting means cooperating with said guiding means and with said guiding element for moving the latter laterally on said mounting means out of guiding relation with the drill steel as said guiding element concurrently moves bodily along said guiding means, said last mentioned means including cooperating cam and follower elements respectively on said guiding means and on said guiding element and having relative sliding movement as said guiding element moves bodily to impart a lateral movement to said guiding element.

10. In a drill steel guide, the combination

11

comprising a support, a guide arm engageable with a drill steel to be guided, pivot providing and guiding means for mounting said guide arm on said support for pivotal movement in transverse planes about an axis extending longitudinally of said support into and out of guiding relation with the drill steel and for guided bodily movement along a straight path in a longitudinal direction lengthwise of the drill steel, and means cooperating with said mounting means and said guide arm and including cooperating swing-effecting elements having relative movement, one on said guiding means and the other on said arm, for swinging said arm outwardly about its pivot relative to the drill steel as said arm moves bodily on said mounting means.

11. In a drill steel guide, the combination comprising a support, a guide arm engageable with a drill steel to be guided, pivot providing and guiding means for mounting said guide arm on said support for pivotal movement about an axis extending longitudinally of said support into and out of guiding relation with the drill steel and for guided bodily movement along a straight path in a longitudinal direction lengthwise of the drill steel, and arm swinging means cooperating with said mounting means and said guide arm and including cooperating swing-effecting elements for swinging said arm outwardly about its pivot relative to the drill steel as said arm moves bodily on said guiding means, one of said cooperating swing-effecting elements being movable bodily with said arm and said other element being stationary with respect to said guiding means whereby upon bodily movement of said arm said elements have relative movement to impart a swinging force to said arm.

12. In a drill steel guide, the combination comprising a support, a guide arm engageable with a drill steel to be guided, pivot providing and guiding means for mounting said guide arm on said support for pivotal movement about an axis extending longitudinally of said support into and out of guiding relation with the drill steel and for bodily movement along a straight path lengthwise of the drill steel, and arm swinging means connected to said mounting means and to said arm and including cooperating swing-effecting elements for swinging said arm outwardly about its pivot relative to the drill steel as said arm moves bodily along its guiding means, one of said swinging elements comprising a cam stationary with respect to said guiding means and the other element constituting a cam engaging element movable bodily with said arm, said cam having a cam surface along which said cam engaging element moves during bodily movement of said arm to effect swinging of the latter.

13. In a drill steel guide, the combination comprising a support, a pair of coaxing guide arms engageable with a drill steel to be guided, pivot providing and guiding means for mounting said arms on said support for relative swinging movement relative to said support about parallel axes extending longitudinally of said support toward and from the drill steel and for bodily movement longitudinally of said support in the direction in which said pivotal axes extend, and swing-effecting means connected to said guiding means and to said arms respectively and including cooperating arm swing-effecting elements, having relative movement, one on said guiding means and the other on said arm, for swinging said arms outwardly about their pivots

relative to the drill steel as said arms move bodily along said guiding means.

14. In a drill steel guide, the combination comprising a support, a guiding element engageable with a drill steel to be guided, movement permitting and guiding means for mounting said guiding element on said support for movement in transverse planes laterally into and out of guiding relation with the drill steel and for rectilinear bodily movement in a direction lengthwise of the drill steel, moving means for said guiding element cooperating with said guiding means and said guiding element for moving the latter laterally outwardly into a partially released position with respect to the drill steel as said guiding element moves bodily along its mounting means, and movement-effecting means separate from aforesaid lateral moving means and operative only when said guiding element has moved into its partially released position for automatically moving said guiding element laterally outwardly to its fully released non-guiding position as said guiding element continues to move bodily along its guiding means.

15. In a rock drill of the kind having a support along which a drill steel actuator is guided for movement toward a work, a drill steel guide carried by said support at the front end thereof and including a guide arm engageable with a drill steel to be guided, pivot providing and guiding means for mounting said guide arm on said support for pivotal movement in transverse planes into and out of guiding relation with the drill steel and for rectilinear bodily movement in a direction lengthwise of the drill steel, said actuator as it moves forwardly along said support engaging said arm to move the latter bodily in a forward direction on said guiding means, and arm swinging means connected to said guiding means and to said arm for swinging said arm outwardly about its pivot away from the drill steel as said arm moves in a forward direction bodily on its mounting means, said arm swinging means including cooperating arm swing-effecting elements, one on said guiding means and the other on said arm, having relative movement as said arm moves forwardly bodily as aforesaid.

16. In a drill steel guide, the combination comprising a support, a guide arm engageable with a drill steel to be guided, pivot providing and guiding means for mounting said arm on said support for swinging movement relative thereto about a longitudinal axis parallel with the longitudinal axis of the drill steel toward and from the drill steel and for guiding said arm for rectilinear bodily movement longitudinally relative to said support in the direction in which said pivotal axis extends, and arm swinging means connected to said mounting means and to said arm and including cooperating arm swing-effecting elements having relative movement, one on said guiding means and the other on said arm, for swinging said arm outwardly about its pivot relative to the drill steel as said arm moves bodily along said guiding means.

17. In a drill steel guide, the combination comprising a support, a pair of cooperating guide arms engageable with a drill steel to be guided, pivot providing and guiding means for mounting said arms on said support for relative pivotal movement about axes extending longitudinally of said support in parallelism with the longitudinal axis of the drill steel and for bodily movement along straight paths in the direction of said pivotal axes, and means on said guiding

12

relative to the drill steel as said arms move bodily along said guiding means.

14. In a drill steel guide, the combination comprising a support, a guiding element engageable with a drill steel to be guided, movement permitting and guiding means for mounting said guiding element on said support for movement in transverse planes laterally into and out of guiding relation with the drill steel and for rectilinear bodily movement in a direction lengthwise of the drill steel, moving means for said guiding element cooperating with said guiding means and said guiding element for moving the latter laterally outwardly into a partially released position with respect to the drill steel as said guiding element moves bodily along its mounting means, and movement-effecting means separate from aforesaid lateral moving means and operative only when said guiding element has moved into its partially released position for automatically moving said guiding element laterally outwardly to its fully released non-guiding position as said guiding element continues to move bodily along its guiding means.

15. In a rock drill of the kind having a support along which a drill steel actuator is guided for movement toward a work, a drill steel guide carried by said support at the front end thereof and including a guide arm engageable with a drill steel to be guided, pivot providing and guiding means for mounting said guide arm on said support for pivotal movement in transverse planes into and out of guiding relation with the drill steel and for rectilinear bodily movement in a direction lengthwise of the drill steel, said actuator as it moves forwardly along said support engaging said arm to move the latter bodily in a forward direction on said guiding means, and arm swinging means connected to said guiding means and to said arm for swinging said arm outwardly about its pivot away from the drill steel as said arm moves in a forward direction bodily on its mounting means, said arm swinging means including cooperating arm swing-effecting elements, one on said guiding means and the other on said arm, having relative movement as said arm moves forwardly bodily as aforesaid.

16. In a drill steel guide, the combination comprising a support, a guide arm engageable with a drill steel to be guided, pivot providing and guiding means for mounting said arm on said support for swinging movement relative thereto about a longitudinal axis parallel with the longitudinal axis of the drill steel toward and from the drill steel and for guiding said arm for rectilinear bodily movement longitudinally relative to said support in the direction in which said pivotal axis extends, and arm swinging means connected to said mounting means and to said arm and including cooperating arm swing-effecting elements having relative movement, one on said guiding means and the other on said arm, for swinging said arm outwardly about its pivot relative to the drill steel as said arm moves bodily along said guiding means.

17. In a drill steel guide, the combination comprising a support, a pair of cooperating guide arms engageable with a drill steel to be guided, pivot providing and guiding means for mounting said arms on said support for relative pivotal movement about axes extending longitudinally of said support in parallelism with the longitudinal axis of the drill steel and for bodily movement along straight paths in the direction of said pivotal axes, and means on said guiding

means providing cam surfaces and cam-follower projections on said arms each engageable with and movable relative to the cam surfaces on one of said guiding means whereby when said arms are moved bodily in a forward direction along said guiding means said arms are concurrently swung outwardly about their pivots away from the drill steel.

18. In a drill steel guide, the combination comprising a support, a pair of cooperating guide arms engageable with a drill steel to be guided, pivot providing and guiding means for mounting said arms on said support for relative pivotal movement about axes extending longitudinally of said support in parallelism with the longitudinal axis of the drill steel and for guided bodily movement along straight paths in the direction of said pivotal axes, means on said guiding means providing relatively inclined, oppositely extending, connected cam surfaces and cam-follower projections on said arms respectively having sliding engagement with said cam surfaces whereby when said arms are moved bodily in a forward direction along said guiding means said follower projections move along certain of said cam surfaces to swing said arms outwardly relative to the drill steel into a partially released position, and springs on said pivot providing and guiding means and acting on said arms and effective when said arms are in their partially released position as aforesaid to move said arms bodily in the rearward direction on said guiding means thereby to move said cam-follower projections along the others of said cam surfaces to further swing said arms outwardly relative to the drill steel into their completely released, non-guiding position.

19. In a drill steel guide, a support member, a pair of cooperating guide arms engageable with a drill steel to be guided, pivotal mounting means on said support member including parallel support elements secured to said support member for mounting said guide arms for swinging movement about longitudinal axes parallel to the longitudinal axis of the drill steel into and

5 out of guiding relation with the drill steel, said pivotal mounting means including said parallel support elements for guiding said arms for bodily movement along straight paths lengthwise of the drill steel, said arms having cam follower members near the pivots thereof, and cam tracks on said parallel support elements and having cam surfaces with which said cam follower elements respectively engage for effecting swinging of said arms outwardly about their pivots away from the drill steel as said arms move bodily along said support elements, said cam follower elements moving along said cam surfaces of said cam tracks as said arms move bodily as aforesaid.

10 20. In a drill steel guide, a support member, a pair of cooperating guide arms engageable with a drill steel to be guided, mounting means on said support member for said guide arms including parallel support elements on which said guide arms are pivotally mounted for swinging movement about longitudinal axes parallel to the axis of the drill steel and slidably mounted for bodily movement lengthwise of the drill steel, and means for effecting swinging of said arms outwardly about said longitudinal axes away from said drill steel as said arms move bodily along said support elements in a direction forwardly longitudinally of the drill steel including cam follower members and cam tracks engaged by said follower members connecting said arms and said parallel support elements and imposing on said arms swinging movement about said axes during their forward longitudinal movement aforesaid.
